UNITED STATES PATENT OFFICE.

MAX HERMAN, OF NEW YORK, N. Y.

CUT-FEATHER POMPON.

1,267,548.

Specification of Letters Patent.

Patented May 28, 1918.

Application filed September 21, 1917. Serial No. 192,442.

To all whom it may concern:

Be it known that I, MAX HERMAN, a citizen of the United States, and resident of New York city, in the county of New York and State of New York, have invented certain new and useful Improvements in Cut-Feather Pompoms, of which the following is a specification.

This invention relates to improvements in 10 cut-feather pompons and in the method of making the same, and aims to provide improvements therein.

Pompoms are generally of considerable size and for many years have been made of 15 ostrich feather cuttings. A recent development of this art has been to form them from short lengths or sections of feathers. Obviously, the simulation of the ostrich type depends more or less upon the symmetrical 20 arrangement and appearance of the cut feathers; and, owing to the size of the pompon, the number of feathers employed is comparatively large. As will be understood, any attempt to arrange the individual feathers 25 into a cluster of the desired size while maintaining the desired symmetrical appearance, is practically impossible especially for commercial uses, the difficulty of preserving a definite arrangement of loose feathers 30 of the size required being such as render the production of a satisfactory product more or less of an accident and of prohibitive cost.

Owing to these difficulties, it has become 35 the practice to form the cluster by a step process, the feathers being gathered into small groups or bunches, each bunch being arranged symmetrically, the inner end of the bunch being placed in a compact formation and wrapped or bound with wire, a portion of the wire being carried beyond the wrapped portion to form a bunch stem. Since the number of feathers used in forming the bunch is comparatively small, the 40 difficulty of providing the desired uniform and symmetrical arrangement is very materially reduced.

The desired number of these bunches are then gathered or grouped into a cluster, with 45 the bunches symmetrically arranged, after

which the wire bunch stems are wrapped or bound together by a wire binding, the wire stem formation permitting the necessary bending or manipulation of the bunch to properly position it within the cluster without materially distorting the bunch formation through manipulating the wrapped 55 ends of the feathers of the bunch.

While the resulting product forms a neat and attractive appearance, it has the serious 60 disadvantage of being easily damaged or marred, the application of pressure on the pompon, as, for instance, by crushing it, producing indentations or cleavages in the exposed face of the pompon. This is due 65 to the fact that such pressure tends to move the bunch bodily, and since the wire stem is bendable, the bunch movement disturbs the normal arrangement, the change remaining 70 unless an expert manipulation is had to restore the original condition, a more or less difficult matter without separating the bunches, and again assembling them in the desired relation.

The present invention is designed to produce 75 a pompon of this type which is not only superior to the pompon thus formed in appearance, but which, in addition, has the characteristic of being unaffected by pressure application, pressure or crushing of the 80 pompon providing no permanent indentation or cleavage of the surface of the pompon, the feathers being relatively "set" and being free from liability of removal by shaking 85 of the pompon or by stroking the feathers with the palm of the hand.

To these and other ends, therefore, the nature of which will be readily understood as the invention is hereinafter described, said invention consists in the improved construction 90 of pompon and the method of producing the same, hereinafter more fully described, illustrated in the accompanying drawings, and more fully pointed out in the appended claims.

In the drawing, Figure 1 illustrates a cut-feather pompon as heretofore constructed and showing an indentation in the surface of the feathers, such as may be produced by a crush or a pressure;

100

Fig. 2 illustrates a single feather, of which my pompon is made, a number of which gathered together form small bunches;

Fig. 3 illustrates a small bunch made up of feathers;

Fig. 4 illustrates a number of small bunches gathered together to form a single bunch, according to the present invention; and

Fig. 5 illustrates a completed pompon made by the present process.

The method of producing a pompon from cut feathers, as heretofore practised, is indicated in Figs. 1 to 3, Fig. 2 indicating at 15 *a* a length or section of a feather employed, Fig. 3 indicating the grouping of the individual feathers into a bunch *A*, the inner ends of the feathers being bound or wrapped together by a wire strand *b* which is arranged so as to produce a wire stem *b'* which forms the bunch stem.

A number of these bunches are then grouped into a cluster as shown somewhat in Fig. 1, the wire bunch stems being bound 25 or wrapped together by a wire strand *b''* to form the pompon stem. As indicated in Fig. 1, the grouping of the bunches requires that the wrapped stems of the bunches extend at different angles from the wire 30 bunch stems, and hence the wrapping *b''* practically extends only over the stems *b'*.

Obviously, any material pressure or crushing action will shift or bend the affected bunch at the point where its wire 35 stem emerges from the wrapped stems *b''*, thus changing the general appearance, as, for instance, shown in Fig. 1. And to attempt to restore it becomes a more or less difficult matter.

In producing the pompon of the present invention, the method above indicated is substantially followed in order that the desired grouping of the bunches can be had in a simple and efficient manner. However, 40 when the cluster is completed by the application of wrapping *b''*, additional operations are provided. The first operation is to bring the inner ends of the unwound portions of the bunches into compact arrangement and with the desired symmetry, after 45 which a wrapping or binding *c* is applied about these ends beyond or above the wrapped feather stems of the bunches, producing an embryo pompon formation such as is disclosed, for instance, in Fig. 4. As 50 will be understood, this wrapping *c* is made on the feather formation alone and acts to bind the unwound portions of the feathers into the desired uniform and symmetrical 55 arrangement, an arrangement which is unaffected by pressure since any crushing effect is placed on individual feathers which 60 will yield but return when the pressure is relieved unless actually broken.

When it is desired to complete the pompon, it is necessary only to sever the wrapped feather and bunch stems below wrapping *c*—these stems thus becoming temporary stems instead of the permanent stems of the previous formations—and applying a stem *D*, which may be secured to the completed cluster in suitable manner, as by passing a wire through the bound or wrapped portion of the cluster and turning the end of the wire down inside of the 75 cluster.

As will be understood, removal of the temporary stems relieves the feathers from the restraint of the bunch conditions, and the feathers may therefore readily spread 80 out to a configuration somewhat like that shown in Fig. 5, producing a finished product much superior in appearance to that heretofore provided.

My improved pompon may be crushed or 85 pressed upon, as is likely to occur during ordinary usage, without receiving cleavages or indentations, as shown in Fig. 1.

What I claim is—

1. A pompon formation comprising a 90 plurality of bunches of cut feathers assembled in cluster formation, each bunch consisting of a plurality of individual feathers in arranged symmetry with one end of the feathers compacted and bound or wrapped into a pack formation and having a wire bunch stem projecting therefrom, the assembly of bunches being in arranged symmetry and having the bunch stems wrapped or bound to provide a pompon stem, and assembled bunches being collectively wrapped or bound into pack formation beyond the bunch wrappings to maintain the relative symmetry of the feathers of a bunch and of the assembled cluster, whereby a pompon 105 may be completed by severing the wrapped or bound portions of the assembly with the exception of such collective wrapping and by the addition of a stem.

2. The method of making pompons from 110 cut feathers which consists in forming a plurality of bunches of cut feathers arranged symmetrically and having a temporary wrapped binding stem and a projecting temporary wire bunch stem, assembling 115 the bunches into a symmetrical cluster with the bunch stems wrapped to produce a temporary pompon stem, binding the assembly together by an external wrapping or binding adjacent the temporary binding stems, 120 and severing the temporary binding, bunch and pompon stems.

3. The method of making pompons from 125 cut feathers which consists in forming a plurality of bunches of cut feathers arranged symmetrically and having a temporary wrapped binding stem and a projecting temporary wire bunch stem, assem-

bling the bunches into a symmetrical cluster with the bunch stems wrapped to produce a temporary pompon stem, binding the assembly together by an external wrapping or binding adjacent the temporary binding stems, and severing the temporary binding,

bunch and pompon stems, and adding a stem to the formation.

Signed at New York in the county of New York and State of New York this 19th day 10 of September A. D. 1917.

MAX HERMAN.
